SAFETY VOLTAGE DETECTOR

Albert E. West, San Francisco, Calif.

Application March 16, 1953, Serial No. 342,635

1 Claim. (Cl. 324—72.5)

An object of my invention is to provide a safety voltage detector which is an improvement over my patented device, Patent Number 2,500,725, issued March 14, 1950. In the patent I show a portable safety voltage detector comprising two staffs for the purpose of checking the line wires and other live contacts to see whether a current at a high voltage is passing through the wires before the lineman starts his work. The main staff is provided with a neon lamp and the lamp is electrically connected in a circuit that extends from the main staff to the auxiliary staff so that when the two staffs contact two high tension lines, the neon lamp will be energized if a high voltage current is flowing through the lines.

The current flowing through the patented device is insulated from the outer surfaces of the device so that it cannot reach the operator. Furthermore, any creepage current flowing along the outer or inner surfaces of the patented device, will be carried to ground before it can reach the operator. This arrangement permits the patented device to be used in rainy weather with safety.

Safety regulations require two linemen to work on a pole or when contacting or handling high voltage circuits or equipment. One man would handle the main staff and the other man, the auxiliary staff.

An object of my present invention is to provide a safety voltage detector in which both staffs carry neon lamps and in addition both staffs carry kv. voltmeters. When therefore a live line or equipment is contacted by a lineman holding the auxiliary staff, he will notice a glow in the neon tube on his staff and at the same time the lineman holding the main staff will notice a glow in the neon tube on his staff, thus indicating to both men that the line or equipment is alive.

In phasing out lines or equipment, one lineman contacts one line or equipment with the auxiliary staff and the other lineman contacts another line or equipment with the main staff and both men will notice a glow in the neon lamp on his staff and a voltage reading from the kv. meter on his staff which will indicate whether the lines or equipment are on the same phase or a different phase.

Each lineman receives the same check from the neon lamp on the condition of the line or equipment and in addition, a voltage reading when both staffs are contacted to the line or equipment and each lineman can satisfy himself as to the condition of the line or equipment and convey his information to a foreman on the ground who in turn thus receives a double check on the condition of the line or equipment being tested. The neon lamp will be partially energized and will glow when the staff to which it is attached is brought into the vicinity of a high tension wire in which a current is flowing. When both staffs actually contact the high voltage wires, the neon lamps are brought up to full brilliance.

The wire that interconnects the two staffs, carries no more than approximately one milliampere at any time regardless of what voltage exists in the lines being tested. It is known that a sixty cycle A. C. current of nine milliamperes is safe to handle. The neon lamps and the kv.

2

meters are each provided with shunt resistances, so that in case of failure of either lamp or either meter, the remaining electrical indicators will continue to function.

Other objects and advantages will appear in the following specification, and the novel features of the device will be particularly pointed out in the appended claims.

My invention is illustrated in the accompanying drawing forming a part of this application, in which:

Figure 1 is a side elevation of the main and auxiliary staffs shown electrically connected and provided with a ground wire;

Figure 2 is an enlarged section taken along the line II—II of Figure 1;

Figure 3 is a sectional view through one of the staffs; and

Figure 4 is a wiring diagram of the electrical circuit used in the device.

While I have shown only the preferred form of my invention, it should be understood that various changes or modifications may be made within the scope of the appended claims without departing from the spirit and scope of the invention.

In carrying out my invention, I provide a main staff indicated generally at A in Figure 1 and an auxiliary staff indicated generally at B. In Figure 3, a vertical section through the auxiliary staff B is illustrated and since both staffs are substantially identical in construction, a description of the auxiliary staff B will be given and similar parts in the staff A will be given corresponding numerals to the parts in the staff B, except that the numerals for the parts in the staff A will be primed.

An insulating tube 1 forms the main body for the auxiliary staff B and Figure 1 illustrates the insulating tube 1' for the main staff A. A metal hook 2 is placed at the top of the body 1 for the auxiliary staff B and an electric terminal 3 is placed at the top of the body 1' for the main staff A.

The body 1 carries an insulating shoulder 4 that is placed below the upper end of the body. A petticoat insulator 5 is positioned under the shoulder 4. I show a triple petticoat insulator in Figure 3, and this type is used where the staffs are to check high tension lines ranging from two to thirty-five kilovolts. Where lines carry from two to twenty-five kilovolts, a double petticoat insulator will be used rather than the triple petticoat one illustrated. A single petticoat insulator is used on staffs checking high tension lines from one to fifteen kilovolts and where the voltage in the lines runs up to seventy kilovolts, two triple petticoat insulators are used, one being disposed above the other on the body 1.

A base 6 is placed below the petticoat insulator 5 and this base carries a kv. voltmeter 7 and a neon lamp 8. The voltmeter 7 is a one millampere ammeter calibrated in kilovolts. The neon tube has a light output of about three thousand hours. The kv. voltmeter is mounted in a casing 9 and the neon tube is mounted in a casing 10. Both casings permit the reading of the current indicators 7 and 8 by a person holding the lower end of the tube 1 and looking upwardly toward the top of the tube.

An internal electrical barrier 11 made of insulating material is mounted within the tubular body 1, see Figure 3. An electrical "ground" collar 12 is attached to the outer surface of the body 1 near the hand grip portion B1 of the body. An inner metal ring 13 is placed within the tubular body 1 and the collar and ring are held in place and electrically connected together by a bolt 14 and a wing nut 15. An insulating shoulder 16 is placed just above the collar 12 and a second insulating shoulder 17 is placed just below the collar. The shoulders 16 and 17 are large enough to prevent an operator's hands from touching the collar 12.

Referring to Figure 1, it will be noted that an extension insulating handle 18 can be slipped over the lower end of the body 1 for increasing its length where desired. The top of the extension handle will contact an insulating sleeve 19 that in turn abuts the undersurface of the shoulder 17. The extension sleeve is removably held in place by a set screw 20 which passes through an opening (not shown) in the body 1 and is received in a threaded opening 21 provided in an insulating petition 22.

Both staffs A and B are electrically connected together by a cable 23 that extends from a socket 24 in the base 6 of the auxiliary staff B, to a socket 24' in the base 6' of the main staff A. The cable 23 is ten to fifteen feet or more in length and is enclosed in an insulating rubber tube 25. It is possible for a lineman to grasp the main staff A, and a second lineman to grasp the auxiliary staff B, and each man be free to move up to ten to fifteen feet away from each other when testing high voltage lines or other equipment.

In Figure 1, I show a ground wire 26 with a clamp 27 adapted to removably grip the collar 12. A second clamp 28, connected at the other end of the wire 26 is used for grounding the wire such as to a metal object 29. The two staffs A and B have their collars 12' and 12, respectively, electrically interconnected by a wire 30 that is connected to the clamp 27 at one end and has its other end provided with a clamp 31 that is removably secured to the collar 12' on the main staff A.

Any stray electricity that creeps down the outside or inside of the tubular bodies 1 and 1' is picked up by the collars 12 and 12' or rings 13 and 13' and is conveyed by the wires 30 and 26 to ground before it can reach the hand grip portions A' and B', or the extensions 18 and 18' if used. The petticoat insulators 5 and 5' provide a dry space within the insulators to prevent the external creeping of electricity down along the outer surfaces of the staffs A and B when they are used in rainy weather.

It is best now to describe the wiring diagram of Figure 4. A resistor 32 is electrically connected to the hook 2 and is housed within the upper portion of the tubular body 1. Another resistor 32' is electrically connected to the electric terminal 3 and is housed within the upper portion of the tubular body 1'. Each resistor 32 and 32' is approximately eighteen megohms. A wire 33 leads from the resistor 32 to a calibrating resistor 34 of approximately four megohms. A wire 35 connects the calibrating resistor with the kv. voltmeter 7.

It will be noted from Figure 4, that a by-pass resistor 36 of approximately 70,000 ohms is shunted across the kv. voltmeter 7 and carries the electric current if for any reason the voltmeter should fail to operate. The by-pass or shunting resistor is housed within the same casing 9 that houses the voltmeter 7. A wire 37 electrically connects the neon tube 8 with the kv. voltmeter 7 so that the two are in series with each other. Also a by-pass resistor 38 of approximately five megohms is shunted across the neon tube 8 and carries the electric current if for any reason the neon tube should fail to operate. The by-pass resistor 38 is housed within the casing 10.

The cable 23 electrically connects the neon tubes 8 and 8' together in series. Figure 4 further shows the "ground" collars 12 and 12' interconnected electrically by the wire 30, and the wire 26 leads from the collar 12 to ground 29. When the staffs A and B are connected to high tension wires, current will flow from the hook 2, through the resistor 32, wire 33, and calibrating resistor 34. From here the current will flow through wire 35 to kv. voltmeter 7 and on through wire 37 to the neon tube 8.

Since the main staff A is electrically connected to the auxiliary staff B by the wire 23, the current will flow from the neon tube 8 to the neon tube 8' and thence through the wire 37' to the kv. voltmeter 7' and on to the electric terminal 3 by means of the wire 35', calibrating resistor

34', wire 33', and the resistor 32'. In case either one of the kv. voltmeters 7 and 7' and either one of the neon tubes 8 and 8' should burn out, the by-pass resistors 36, 38, 38' or 36', would permit the current to be shunted around the burned out electrical indicator and thus the remaining electrical indicators would continue to function.

The safety voltage detectors provide the maximum protection against dangerous high voltage current in both dry and wet weather. The high voltage current is reduced to a low non-hazardous value at the top of the two staffs so that the linemen do not handle high voltage current at any time. The safety voltage detectors combine "hot sticks" leads for testing potential transformers and meters. Phasing and other tests on lines or equipment having voltages from 1000 to 70,000 volts A. C. at twenty-five cycles to one hundred and thirty-three cycles can be carried out.

The device can be used in dry or cramped locations, as in manholes or on unsheathed cables or on outside lines in the rain, snow and ice conditions. In wet or moist weather, the extension handles 18 and 18' are put on the handles B' and A', respectively. This gives a longer reach. When the device is used in dry weather, it is not necessary to use the extension handles, nor is it necessary to use the ground wire connection.

When either staff is brought near a line or other equipment that has a high voltage current therein, the neon tube will glow even before contact is made. This will warn the operator that he is in the vicinity of high voltage current and caution should be exercised. As soon as contact is made with the two staffs, the neon tube will increase to full brilliancy. At the same time the kv. voltmeters will give the exact reading as to the number of volts in the lines or in the equipment being tested. The two kinds of electrical indicators are each independent of the other. Yet the neon tube gives the initial warning by glowing before contact is made and then the kv. voltmeters will give an accurate reading in volts after contact is made. The total electrical resistance of one staff plus the total electrical resistance of the other staff will cause a negligible amount of current to flow through the line 23 that interconnects the staffs.

A dowel pin 39 is used for securing the bushing 24 and the rubber tubing 25 to the base 6. The dowel pin penetrates the base 6, bushing 24 and the rubber tubing 25, to hold them all in place on the base 6.

In actual practice, the resistors 32 and 32' are sealed in a high dielectric insulating tube, not shown, and the tubes are placed within the upper portions of the hollow staffs 1 and 1'. The placing of a resistor 32 in the staff B and a resistor 32' in the staff A results in an approximately equal amount of resistance being placed within each staff, thereby adding an additional safety feature in case human contact is made with the high voltage cable 23 that extends between the two staffs.

I claim:

A safety voltage detector for high voltage lines and the like comprising a main staff, an electrical terminal arranged at the top of the staff and adapted to contact a "ground" or a high tension wire having electricity of a certain phase flowing therethrough; a resistor mounted in the staff and being electrically connected to the terminal; a kv. voltmeter carried by the staff and connected in series with the resistor, a second resistor shunted across the voltmeter and designed to carry the electric current should the voltmeter fail to function; an auxiliary staff, a second electrical terminal arranged at the top of the auxiliary staff and adapted to contact a high tension wire having a phase of electricity flowing therethrough which is different from the other high tension wire to be contacted; a third resistor mounted in the auxiliary staff and being electrically connected to the second terminal; a neon tube carried by the auxiliary staff and being connected in series with the third resistor; a fourth resistor

shunted across the neon tube and designed to carry the electric current should the tube fail to function; and an elongated flexible wire electrically connected to the voltmeter of the main staff and to the neon tube of the auxiliary staff so that the neon lamp will indicate that there is high tension current flowing through the line when the terminal of the auxiliary staff contacts the line and the voltmeter will indicate the voltage when the terminal of the main staff contacts the "ground" or the other

high tension wire that is of a different electrical phase from the wire contacted by the terminal of the auxiliary staff.
